(57) **CLAIM**

The ornamental design for a wearable electronic device with transitional graphical user interface, as shown and described.

DESCRIPTION

FIG. 1 is a front view of a wearable electronic device with transitional graphical user interface showing the first image of the first embodiment of our new design.

FIG. 2 is a front view of the wearable electronic device with transitional graphical user interface showing the second image of the first embodiment.

FIG. 3 is a front view of the wearable electronic device with transitional graphical user interface showing the third image of the first embodiment.

FIG. 4 is a front view of a wearable electronic device with transitional graphical user interface showing the first image of a second embodiment.

FIG. 5 is a front view of a wearable electronic device with transitional graphical user interface showing the second image of the second embodiment.

FIG. 6 is a front view of a wearable electronic device with transitional graphical user interface showing the first image of a third embodiment.

FIG. 7 is a front view of a wearable electronic device with transitional graphical user interface showing the second image of the third embodiment.

FIG. 8 is a front view of a wearable electronic device with transitional graphical user interface showing the third image of the third embodiment.

FIG. 9 is a front view of a wearable device with transitional graphical user interface showing the fourth image of the third embodiment.

FIG. 10 is a front view of a wearable electronic device with transitional graphical user interface showing the fifth image of the third embodiment.

FIG. 11 is a front view of a wearable device with transitional graphical user interface showing the first image of a fourth embodiment.

(Continued)

FIG. 12 is a front view of a wearable electronic device with transitional graphical user interface showing the second image of the fourth embodiment.

FIG. 13 is a front view of a wearable electronic device with transitional graphical user interface showing the third image of the fourth embodiment.

FIG. 14 is a front view of a wearable electronic device with transitional graphical user interface showing the fourth image of the fourth embodiment.

FIG. 15 is a front view of a wearable electronic device with transitional graphical user interface showing the first image of a fifth embodiment.

FIG. 16 is a front view of a wearable electronic device with transitional graphical user interface showing the second image of the fifth embodiment.

FIG. 17 is a front view of a wearable electronic device with transitional graphical user interface showing the third image of the fifth embodiment; and,

FIG. 18 is a front view of a wearable electronic device with transitional graphical user interface showing the fourth image of the fifth embodiment.

In the first embodiment, the appearance of the transitional graphical user interface sequentially transitions between the images shown in FIGS. 1 to 3. In the second embodiment, the appearance of the transitional graphical user interface sequentially transitions between the images shown in FIGS. 4 to 5. In the third embodiment, the appearance of the transitional graphical user interface sequentially transitions between the images shown in FIGS. 6 through 10. In the fourth embodiment, the appearance of the transitional graphical user interface sequentially transitions between the images shown in FIGS. 11 through 14. In the fifth embodiment, the appearance of the transitional graphical user interface sequentially transitions between the images shown in FIGS. 15 through 18. The process or period in which one image transitions to another image forms no part of the claimed design.

The ornamental design which is claimed is shown in solid lines in the drawings.

The wearable electronic device with transitional graphic user interface is flat. The undisclosed sides, top, bottom, and rear views are not part of the claimed design.

1 Claim, 18 Drawing Sheets
